CONTROLLING ARRANGEMENT FOR A
GAS BURNER

Friedrich Wilhelm Stockmeyer and Wilhelm Römmelt, Stuttgart, Germany, assignors to Junkers & Co., Gesellschaft mit beschränkter Haftung, Dessau, Germany

Application June 6, 1932, Serial No. 615,676
In Germany June 18, 1931

8 Claims. (Cl. 158—117.1)

The present invention relates to gas burners and more particularly to safety switching arrangements for the main gas valves of burners in which the controlling or operating diaphragm 5 of the main valve is operated by alterations in pressure on one side thereof produced by the opening or closing of switching valves in a branch pipe branching off the main gas pipe.

The invention is especially concerned with 10 switching arrangements in which the outlet of the control pipe terminates in a pilot burner, which is governed by an automatic valve (for example, a thermostatic valve) actuated by the pilot flame. In order to enable the extinguished 15 pilot flame to be re-ignited, a pipe is usually provided which connects the pilot burner directly with the main pipe whilst bypassing the closed pilot thermostatic valve, and is controlled by an automatically closing valve, for example 20 a spring urged press-button which is operable by hand.

This known switching arrangement has several drawbacks. If, for instance, the pilot flame is fed for re-ignition by the aid of the by-pass 25 pipe, the pilot valve, operated by the heat of the pilot flame, opens which thus simultaneously causes the main valve to open because the controlling gas pressure which hitherto held the main valve closed at once escapes through the 30 opened pilot valve. The main burner will thus receive gas directly after the ignition of the pilot flame, which gas now ignites at the pilot flame and endangers the person engaged in the igniting operation. If the supply of gas to the pilot 35 flame through the by-pass is cut off the pilot flame may at once go out because air very quickly collects in the closed controlling pipe and produces the extinction of the pilot flame until it is fully displaced from the controlling 40 and by-pass pipe. If now the lighting of the pilot flame is repeated, the burner gas which emerged unburnt at the first ignition of the pilot flame is ignited and may cause an explosion.

These drawbacks are removed according to the 45 invention in that the switch arrangement which controls the by-pass pipe when in the open position simultaneously automatically closes the valve member of the main valve for example by connecting the control chamber of said main 50 valve with the main pipe by a pipe of such width that a reduction in pressure in the control chamber and thus an opening of the main valve is prevented on the opening of the by-pass valve. If the switching valve is again closed, however, 55 the valve member of the main valve is free to

open because the closing of the switch valve 5 interrupts the above-mentioned connection of the controlling chamber with the main pipe, so that the main valve can open. The invention thus permits the main valve to be held closed during the ignition of the pilot flame and until the pilot flame burns quietly and regularly.

It is particularly of advantage if the ignition gas is led through the controlling chamber before it reaches the pilot burner, because the powerful 10 gas current then has an opportunity of quickly scavenging out the air which has collected in the control chamber and the control pipe. Preferably, the small-diameter control pipe leading from the control chamber to the pilot burner is 15 arranged within the wide igniting gas pipe, so that it forms with this latter a double tube and is protected. At the same time the igniting pipe standing only temporarily under pressure prevents the escape into the room of leaking gas 20 from the control pipe which stands constantly under pressure.

The invention is shown in the drawings, in which:—

Fig. 1 is a diagrammatic view of one form of 25 gas burner and control arrangement therefor embodying the invention with the main burner valve and the pilot burner valve in closed position;

Fig. 2 is a view similar to Fig. 1, but showing 30 the main burner valve in closed position and the pilot burner valve in open position and the pilot flame on;

Fig. 3 is a view similar to Fig. 1 but showing 35 both the main burner valve and the pilot burner valve in open position and both burners lighted;

Figure 4 is a partial vertical sectional view of 40 a suitable form of construction of main burner valve and control arrangement therefor corresponding in general principle and mode of operation to the arrangement diagrammatically illustrated in Figures 1 to 3.

Fig. 5 is a diagrammatic view of a third embodiment of the invention, showing the main burner valve and the pilot-burner valve in 45 closed position;

Fig. 6 is a view similar to Fig. 5 but showing the main burner valve closed and the pilot-burner valve open and the pilot flame on;

Fig. 7 is a view similar to Fig. 5 but showing 50 the main burner valve and the pilot burner valve both in open position and both burners lighted;

Fig. 8 is a partial vertical sectional view of a 55 fourth embodiment of the invention showing a suitable form of construction of main burner

valve and control arrangement therefor corresponding in general principle and mode of operation to the arrangement diagrammatically illustrated in Figs. 5-7; and

5 Fig. 9 is a partial longitudinal sectional view on a larger scale than the scale of the preceding figures of a pilot burner and thermostatic valve of the type employed in all the arrangements of the preceding views.

10 Throughout the drawings the main valve is denoted by A, the main burner by B, the pilot burner by C, and the igniting switch by D. In all the forms, also, the main valve A is inserted between the main pipe 10 and the burner pipe 11.

15 Its valve plate 12 is attached to a diaphragm 13, above which a control chamber 14 is arranged.

Referring now more particularly to the arrangement shown in Figs. 1 to 3 inclusive, the control chamber 14 communicates by a pipe 16 provided with a throttle 15 with the main pipe 10, and by a controlling pipe 17, 18 with the pilot burner C. The pilot burner C has a thermostat valve 19 controlled by the heat of the pilot flame, which valve closes the outlet of the controlling pipe 18 as soon as the pilot flame goes out (Fig. 1). By the closing of the controlling pipe, the controlling gas flowing through the throttle 15 is dammed up in the controlling chamber 14 of the main valve, so that it presses the diaphragm 13 downwards and closes the main valve. For the re-ignition of the pilot flame, a pipe 20, 21 is provided which branches from the main pipe 10, and whilst by-passing the igniting valve 19, opens into the casing of the pilot burner C.

30 In the ignition pipe 20, 21, is provided an igniting valve D which has a passage 22 and can be opened and closed by hand. In Fig. 1, the valve D is shown as closed and therefore as interrupting the ignition pipe 20, 21. In the opened position of the valve D, the passage 22 connects the gas main 10 with the pilot burner C, as shown in Fig. 2.

According to the present invention, the igniting valve D also constitutes a switch valve and is provided with a cross bore 23, which in the open position of the switch connects the passage 22 with a pipe 24 which is connected to the controlling pipe 17. If with this switch arrangement the igniting switch D is opened (Fig. 2), the igniting gas flows not only through the igniting pipe 21 to the pilot burner C, but also through the pipes 24, 17 into the control chamber 14 of the main valve A and holds the main valve closed, notwithstanding that the thermostatic valve 19 has been opened by the heat of the pilot flame. To open the main valve A for flow of the main gas to the burner B, the igniting switch D is again closed (Fig. 3). This closing of the valve D interrupts the flow of gas from the pipe 20 through the pipe 24 to the control chamber and through by-pass pipe 21 to the pilot burner, and consequently the control chamber 14 receives only the controlling gas flowing through the narrow throttle 15, and this controlling gas then flows from the control chamber 14 through the controlling pipes 17, 18 to the pilot burner. The result is that the main valve A opens and lets the main gas flow to the main burner B, where it is ignited with certainty at the pilot flame. Thus, the ignition and switch valve D and its pipe connections provide means for holding the main gas valve closed during the act of igniting the pilot flame 75 and until that flame burns quietly and regularly.

The construction shown in Fig. 4 utilizes the switch arrangement just described, whilst employing a press-knob 25 as the igniting switch D. The branch pipe 16 here starts from the high pressure chamber 26 of the main valve and opens by the throttle 15 into the control chamber 14 above the diaphragm 13. From here the control pipe 17, 18 leads to the pilot burner C. This latter consists of a casing 27 which is closed by a thermostat disc 28 having a burner opening 29. The pilot valve 19 is attached to the thermostat disc 28 and this valve closes the end of the control pipe 18 when the pilot flame is not burning. When however the pilot flame is lit, the valve is lifted from its seat by the thermostat disc 28 arching. The igniting pipe 20 branches from the branch pipe 16 and opens into the passage 22 of the press knob 25. The cross passage 23 branches from the passage 22. When the press-knob is at rest, the two passages 22, 23 are closed. When the press-knob is depressed, the passage 22 comes opposite the igniting pipe 21, and the passage 23 opposite the pipe 24 which opens into the control pipe 17, 18. The mode of working of this arrangement is the same as was described with reference to Figs. 1-3. The small-diameter control pipe 18 which leads from the main valve casing to the pilot burner C is laid in the interior of a wide pipe which serves as the igniting pipe 21. The two pipes 18, 21 together thus form a double pipe in the inner part 18 of which pressure constantly prevails, whilst the outer part 21 is only temporarily traversed by gas. The small-diameter but more strongly stressed control pipe is thus 35 protected by the wide but more weakly stressed igniting pipe 21.

The switching arrangement shown in Figs. 5-7 differs from the switching arrangement shown in Figs. 1-3 in not having a direct connection between the two parts 20, 21 of the igniting pipe. The part 20 of the igniting pipe, on the contrary, is connected in the open position of the switch (Fig. 6) by a passage 30 with a pipe 31 which leads to the control chamber 14 of the main valve A. The branch pipe 17, 18 passes out from the control chamber and from this pipe branches a pipe 32, which is connected through the switch D by means of a passage 33 with the part 21 of the igniting pipe. When the igniting switch D is opened (Fig. 6), the igniting gas must thus flow through the pipe 31 to the control chamber 14 and through this by the part 17 of the control pipe and pipes 32, 21 to the pilot burner C, where it is ignited. If now the igniting or pilot valve 19 is opened, the igniting gas also flows through the part 18 of the control pipe, so that thus the control chamber 14 and the whole control pipe 17, 18 are flushed by the powerful current of igniting gas and 60 freed from the air which has accumulated. The mode of working is, for the rest, the same as in the switch arrangement shown in Figs. 1-3.

Figure 8 shows in vertical section a suitable construction of switching arrangement similar in general principle and mode of operation to that shown in Figs. 5-7. The controlling gas here flows through the throttle 15 inserted in the diaphragm 13 directly into the control chamber 14 and from there through the passage 18 to the pilot burner C, the construction of which is the same as in Fig. 4. The igniting gas is taken by the pipe 20 from the high pressure chamber 26 of the main valve A and led through the passage 30 of the press-knob 25 and the 75

passage 31 to the control chamber 14. From the control chamber 14 the igniting gas flows through the pipe 32 again to the press-knob and through its passage 33 and through the part 2f 5 of the igniting pipe to the pilot burner.

Although the diameters of the various conduits or pipes of the control arrangements or systems shown in the illustrated embodiments of the invention may vary with the diameter of 10 the main gas line 10, 11, they are, of course, in all instances substantially smaller than the diameter of the main gas line. A suitable minimum diameter for the pipes or conduits 16, 17, 18, 20 and 21 shown in all the illustrated embodiments of the invention, for the passages 22, 23 in the valve D of Figs. 1-4, for the passages 30, 33 in the valve D shown in Figs. 5-8, and for the pipes or conduits 31, 32 also shown in Figs. 5-8 is 5 mm. A suitable minimum diameter for 20 the throttle 15 in the pipe or conduit 16 of Figs. 1-7 and in the diaphragm 13 of Fig. 8 is 0.7 mm. while a suitable minimum diameter for the burner opening 29 in the thermostatic disc 28 of the pilot burner, illustrated in Figs. 4 and 9, is 1.6 mm. The purpose served by having the pilot pipe 17, 18 and the pilot burner opening 29 of larger diameter than the throttle 15 is apparent from a consideration of Fig. 3. As 25 there shown, when the pilot burner has been lighted and the pilot burner valve 19 has been moved by the outward arching of the thermostatic disc to open position, and the switch valve D has been closed, the flow of gas to feed the pilot flame is from the main gas pipe 10 on the 30 pressure side of the main burner valve through the pipe 16 and the throttle 15 therein to the control chamber 14 above the diaphragm of the main burner valve and from that chamber through the pipes 17, 18 to the pilot burner opening. As the control chamber 14 is between 35 the throttle 15 and the pilot-burner opening and the latter is of larger diameter than the throttle and on its low pressure side, it follows that the feed of gas to the pilot burner opening reduces the gas pressure in the control chamber 40 below the pressure on the opposite side of the diaphragm of the main burner valve and thereby effects the opening of that valve as shown in Fig. 3. The arrangement and mode of operation are the same in principle, of course, in the 45 other forms of the invention.

As shown in Fig. 9, the thermostatic valve comprises a single metallic disc 28 over the mouth of the casing 27 of the pilot burner, to 50 which casing the ignition gas pipe 21 and the pilot pipe 18 lead. The valve member 19 is connected to the under side of the diaphragm so that as the diaphragm expands and contracts and thereby arches outwardly and flattens inwardly, the valve member 19 is moved from and toward the exit opening of the pipe 18 in a manner to open and close that opening.

We declare, that what we claim is:

1. A controlling arrangement for a gas burner comprising the combination with a gas burner, of a valve chest, a main supply valve and diaphragm therefor dividing said valve chest into a main gas chamber and a control chamber and operable under difference of pressure in the 55 chambers to control the supply of gas to the burner, a gas main connected to said main gas chamber, a burner conduit between the burner and said main gas chamber controlled by the said valve, a pilot burner, a pilot conduit between the control chamber and said pilot burner, a pilot conduit between the 60 control chamber and said pilot burner, a thermostatic valve responsive to the heat of said pilot burner and operative to control said pilot conduit, a throttled connection between said chambers, a pressure equalizing conduit between the gas main and said control chamber, a by-pass conduit around said thermostatic valve and extending between said pilot conduit and said 65

thermostatic valve responsive to the heat of the pilot burner and operative to control said pilot conduit, a throttled connection between the said chambers, a by-pass conduit around said thermostatic valve and extending between the gas main and said pilot burner, and means including a valve in said by-pass conduit automatically connecting said control chamber directly to the main pressure gas supply upon opening said by-pass conduit. 70

2. A controlling arrangement for a gas burner comprising the combination with a gas burner, of a valve chest, a main supply valve and a diaphragm therefor dividing said valve chest into a main gas chamber and a control chamber and operable under difference in pressure in the chambers to control the supply of gas to the burner, a gas main connected to said main gas chamber, a burner conduit between the burner and main gas chamber controlled by the said valve, a pilot burner, a pilot conduit between the control chamber and said pilot burner, a thermostatic valve responsive to the heat of the pilot burner and operative to control said pilot conduit, a throttled connection between the said chambers, a by-pass conduit around said thermostatic valve and extending between said gas main and said pilot burner, a valve controlling said by-pass conduit and operable to connect said pilot burner to and cut it off from said gas main independently of said thermostatic valve, and conduit means controlled by said by-pass valve to connect said by-pass conduit to said control chamber. 75

3. A controlling arrangement for a gas burner comprising the combination with a gas main and a main gas burner, of a valve chest, a main supply valve and diaphragm therefor dividing said valve chest into a main gas chamber and a control chamber and operable under difference of pressure in the chambers to control the supply of gas to the burner, a burner conduit between the burner and main gas chamber controlled by the said valve, a pilot burner, a pilot conduit between the control chamber and said pilot burner, a thermostatic valve responsive to the heat of said pilot burner and operative to control said pilot conduit, a throttled connection between the said chambers, a pressure equalizing conduit between the gas main and said control chamber, a by-pass conduit around said thermostatic valve between said control chamber and said pilot burner and valve means operable to simultaneously open and to simultaneously close said pressure-equalizing conduit and said by-pass conduit. 80

4. A controlling arrangement for a gas burner comprising the combination with a gas burner, of a valve chest, a main supply valve and diaphragm therefor dividing said valve chest into a main gas chamber and a control chamber and operable under difference of pressure in the chambers to control the supply of gas to the burner, a gas main connected to said main gas chamber, a burner conduit between the burner and main gas chamber controlled by the said valve, a pilot burner, a pilot conduit between the control chamber and said pilot burner, a thermostatic valve responsive to the heat of said pilot burner and operative to control said pilot conduit, a throttled connection between said chambers, a pressure equalizing conduit between the gas main and said control chamber, a by-pass conduit around said thermostatic valve and extending between said pilot conduit and said 85

pilot burner and valve means operable to simultaneously open and to simultaneously close said pressure-equalizing conduit and said by-pass conduit.

5. A controlling arrangement for gas burners comprising the combination with a gas burner, of a main valve casing, a control chamber in said main valve casing, a main gas chamber in said casing having an opening therein for the entrance of main gas, a diaphragm separating said chambers, a valve seat in said casing within said main gas chamber connected with the burner, a valve secured to said diaphragm and seating on said seat, a throttled conduit between said chambers, a pilot burner having a thermostatic disc with an opening therethrough forming the pilot jet and a valve member carried by said disc, a relatively large-diameter pipe secured to said casing and supporting said pilot burner and arranged to deliver gas around said valve member to said pilot jet to start the pilot light, a relatively small-diameter pipe arranged within said larger pipe with its exit opening adjacent said valve member in position to be controlled thereby, a pilot conduit in said main valve casing connecting said smaller pipe and said control chamber, conduit means connecting said main gas chamber and said larger pipe to supply gas to said pilot jet, and valve means in said casing controlling said conduit means.
6. A controlling arrangement for gas burners comprising the combination with a gas burner, of a main valve casing, a control chamber in said main valve casing, a main gas chamber in said casing having an opening therein for the entrance of main gas, a diaphragm separating said chambers, a valve seat in said casing within said main gas chamber connected with the burner, a valve secured to said diaphragm and seating on said seat, a throttled conduit between said chambers, a pilot burner having a thermostatic disc with an opening therethrough forming the pilot jet and a valve member carried by said disc, a relatively large-diameter pipe secured to said casing and supporting said pilot burner and arranged to deliver gas around said valve member to said pilot jet to start the pilot light, a relatively small-diameter pipe arranged within said larger pipe with its exit opening adjacent said valve member in position to be controlled thereby, a pilot conduit in said main valve casing connecting said smaller pipe and said control chamber, a by-pass conduit in said main valve casing around said throttled conduit connecting said main gas chamber with said control chamber and with said larger pipe and a spring urged piston valve working in said main valve casing normally closing said by-pass conduit and manually operable to connect said main gas chamber simultaneously with said control chamber and said larger pipe.

7. A controlling arrangement for a gas burner comprising the combination with a gas main and a main gas burner, of a main gas valve having a valve chest, a valve member and a diaphragm therefor dividing said valve chest into a main gas chamber and a pressure control chamber and operable under differences in fluid pressures in said chambers, said main gas chamber having an inlet connected to said gas main for the supply of gas thereto, an outlet connected to said main gas burner and a seat for

said valve member intermediate said gas inlet and outlet, a throttled connection between the high-pressure or main gas supply side of said main valve and said control chamber, a pilot burner, a pilot conduit leading from said control chamber to said pilot burner to feed gas to said pilot burner when the pilot flame is on, said pilot burner and said pilot conduit each having a greater cross sectional area for the flow of gas therethrough from said control chamber than said throttled connection for the flow of gas therethrough into said control chamber, a thermostatic valve closing said pilot conduit when the pilot flame is extinguished and responsive to the heat of the pilot flame to open said pilot conduit, by-pass conduit means around said throttled connection between the supply side of said main valve and said control chamber and between said control chamber and said pilot burner around said thermostatic valve operative to provide an igniting or starting feed of gas to said pilot burner and to maintain a pressure in said control chamber closing said main supply valve as long as said ignition feed of gas is on, and valve means for controlling said by-pass conduit means.

8. A controlling arrangement for a gas burner comprising the combination with a gas burner and a gas line leading thereto, of a valve chest interposed in said gas line, a diaphragm dividing said chest into a main gas chamber on one side of the diaphragm and a control chamber on the other with the first chamber connected to said gas line, a main gas valve operatively connected with said diaphragm and controlling the feed of gas through said gas line to said burner, a pilot burner having a jet and a gas passage through the body of the pilot burner leading to said jet, a thermostatic pilot valve for said passage having a thermostat element operating in response to the heat of the pilot flame to open said pilot valve and in response to extinguishment of the pilot flame to close said pilot valve, by-pass conduit means connected with said gas line on the high-pressure side of said main valve and with said control chamber and extending around said thermostatic pilot valve to said pilot jet and a by-pass valve controlling the flow of gas from said gas line through said by-pass conduit means to said pilot jet and said control chamber, said by-pass conduit means being operative when its said valve is open to provide an igniting or starting feed of gas to said pilot jet and to maintain a pressure in said control chamber closing said main gas valve as long as said ignition feed of gas to said pilot jet is on, and conduit means connecting said gas line on the high-pressure side of said main valve with said control chamber and the latter with said gas passage in said pilot burner and operating when said by-pass valve is closed and said thermostatic pilot valve is open to feed gas from said gas line through said control chamber to said pilot jet at rates of gas flow into and out of said control chamber so reducing the gas pressure in said control chamber below that in said main gas chamber as to cause said diaphragm to open said main gas valve and maintain it open as long as said last-mentioned feed of gas to the pilot jet is on.

FRIEDRICH WILHELM STOCKMEYER.
